UNITED STATES PATENT OFFICE.

AUGUSTE DONT, OF MANVILLE, RHODE ISLAND.

PICKER STOP-MOTION FOR LOOMS.

SPECIFICATION forming part of Letters Patent No. 783,110, dated February 21, 1905.

Application filed December 1, 1904. Serial No. 235,019.

To all whom it may concern:

Be it known that I, AUGUSTE DONT, a subject of the King of Belgium, residing at Manville, in the county of Providence and State of Rhode Island, have invented a new and useful Improvement in Picker Stop-Motions for Looms, 5 of which the following is a specification.

This invention has reference to an improvement in looms, and more particularly to an 10 improvement in picker stop-motions for looms whereby the throw of the picker-sticks is automatically stopped when required.

When in the operation of weaving a shuttle is about to be thrown through the shed 15 and a box at the opposite end of the lay which is intended to receive the shuttle is by accident or mistake already occupied by a shuttle, it must be evident that the stopping of the first-mentioned shuttle is imperative if a 20 smash is to be prevented. The most positive and quickest method for preventing the throw of the shuttle is by stopping the throw or operation of the picker-sticks.

The object of my invention is to automatically stop the operation of the picker-sticks 25 and the throw of a shuttle when two shuttles are in opposite boxes, thereby preventing the smashing of the warp-threads and liability of injury to the operators.

30 My invention consists in the peculiar and novel construction of a stop-motion for this purpose and its connection with the operative parts of a loom whereby a smash is prevented when two shuttles are in opposite boxes, as will be more fully set forth hereinafter.

Figure 1 is a front view of a loom provided 35 with my improved picker stop-motion, showing the loom partly in section and the stop-motion mechanism in the position it would 40 assume with a shuttle in the left-hand shuttle-box. Fig. 2 is an enlarged detail view of the left-hand part of the stop-motion mechanism, showing the position the mechanism would assume in throwing a shuttle from the 45 left-hand shuttle-box; and Fig. 3 is a detail sectional view of part of the stop-motion mechanism, taken on line X X of Fig. 2.

In the drawings, $a a$ indicate the side frames, 50 a' the lay, $a^2 a^3$ the shuttle-boxes, $a^3 a^3$ the swells, $a^4 a^4$ the picker-sticks, $a^5 a^5$ the floor-

springs, a^6 the rocking rail, $a^7 a^7$ the picker-stick-supporting members on the outer ends of the rocking rail, $a^8 a^8$ the picking-shafts, and $a^9 a^9$ the picking-arms, of a loom. These picking-arms $a^9 a^9$ are changed slightly in construction from the usual picking-arms, so as to have the straight ends $a^{10} a^{10}$ as shown in Figs. 1 and 2.

In applying my improved picker stop-motion to a loom I secure the double bearings b 60 to the lay a' at each end, as shown in Fig. 1. These bearings support the upper feeler-shaft b' and the lower feeler-shaft b^2 . On the left-hand end of the upper feeler-shaft b' is secured the feeler-arm b^3 in a position to bear 65 on a swell a^3 of the left-hand shuttle-boxes a^2 . The lever b^4 is secured to the right-hand end of the upper feeler-shaft b' . On the right-hand end of the lower shaft b^2 is secured the feeler-arm b^5 in a position to bear on a swell of the 70 right-hand shuttle-box, and on the left-hand end of the lower shaft b^2 is secured the lever b^6 . The feeler-arms b^3 and b^5 are held against the swells under spring tension, and the levers b^4 and b^6 are held in their downward positions 75 under the shuttle-boxes by the coiled springs $b^7 b^7$ on the feeler-shafts. The rods $b^8 b^8$ are pivotally secured at their upper ends to the levers b^4 and b^6 . The fingers $c c$ have the upwardly-turned hook-shaped ends $c' c'$ and are 80 adjustably secured to the straight ends $a^{10} a^{10}$ of the picking-arms $a^9 a^9$ by the set-bolts $c^2 c^2$. The hook-shaped ends of the fingers extend outward toward the picker-sticks.

The arms $d d$ have the downwardly-turned 85 hook-shaped inner ends $d' d'$ and the holes d^2 d^2 for pivotally securing the lower ends of the rods $b^8 b^8$ to the arms. These arms $d d$ are pivotally secured at their outer ends to the upper ends of the supporting-links $d^3 d^3$, 90 which in turn are pivotally secured at their lower ends to the picker-stick-supporting members $a^7 a^7$. The connecting-links $d^4 d^4$ are pivotally secured to the upper ends of the supporting-links $d^3 d^3$ and to the picker-straps $d^5 d^5$, which are secured to the picker-sticks $a^4 a^4$ in the usual way.

In the operation of my improved picker stop-motion the entire mechanism of the stop-motion with the exception of the fingers $c c$ 200

on the picker-arms moves in unison with the lay and picker-stick. As the lay reaches its extreme inward position the hooked ends of the arm d come into position over the 5 hooked ends of the fingers c . A picking-arm a^3 is moved in the direction of the arrow by the operation of the usual picking-cones. The hooked end of a finger c engages with the hooked end of an arm d and through the arm 10 d , the link d^4 , the picker-strap d^5 , and the picker-stick a^4 a shuttle is thrown from one shuttle-box to the opposite shuttle-box. If by mistake or other means a shuttle should be in the left-hand shuttle-box and a shuttle was 15 about to be thrown from the right-hand shuttle-box, the outward movement of the swell on the left-hand shuttle-box would move the feeler-arm b^3 outward, partly rotate the shaft b^1 against the tension of the spring b^7 , and 20 through the lever b^4 and the rod b^8 raise the hooked end d' of the arm d out of engagement with the hooked end c' of the finger c on the right-hand side of the loom, thus stopping the throw of the right-hand picker-stick, as shown in Fig. 1, and the outward 25 movement of the swell on the right-hand shuttle-box would move the feeler-arm b^3 outward, partly rotate the shaft b^2 against the tension of the spring b^7 , and through the lever b^6 and 30 the rod b^8 raise the hooked end d' of the arm d out of engagement with the hooked end c' of the finger c on the left-hand side of the loom, stopping the throw of the left-hand picker-stick. Both picker-sticks would now 35 be out of engagement until one of the shuttles is removed by the operator.

Having thus described my invention, I claim as new and desire to secure by Letters Patent—

1. The combination with a loom, of a picker 40 stop-motion consisting of bearings secured to the lay, upper and lower feeler-shafts supported in the bearings, spring-pressed feeler-arms on the shafts adapted to bear on the swells of the shuttle-boxes, levers on the shafts 45 extending under the shuttle-boxes, downwardly-extending rods pivotally secured to the levers, hook-shaped arms at each side of the loom pivotally connected to the picker-sticks and to the downwardly-extending rods, 50 and hook-shaped fingers on the picking-arms of the loom in a position to engage with the hook-shaped arms on the picker-sticks when the lay is in its inward position, as described.

2. The combination with a loom, of a picker

stop-motion having hook-shaped fingers ad- 55 justably secured to the picking-arms of the loom, hook-shaped arms pivotally connected to the picker-sticks, and intermediate mechanism actuated by the swells on the shuttle-boxes to raise the hook-shaped arms on the 60 picker-stick out of engagement with the hook-shaped fingers on the picker-arms, when a shuttle is in the shuttle-box, as described.

3. The combination with a loom, of a picker stop-motion consisting of bearings secured to 65 the lay, upper and lower feeler-shafts supported in the bearings, a feeler-arm on the left end of the upper shaft adapted to bear on a swell of the left-hand shuttle-boxes, a rear- 70 wardly-extending lever on the right end of the upper feeler-shaft, a downwardly-extending rod pivotally secured to the lever, a feeler- 75 arm on the right end of the lower feeler-shaft adapted to bear on a swell of the right-hand shuttle-boxes, a rearwardly-extending lever 80 on the left end of the lower feeler-shaft, a downwardly-extending rod pivotally secured to the lever, hook-shaped arms at each side of the loom pivotally connected to the picker- 85 sticks and to the downwardly-extending rods, 90 and hook-shaped fingers on the picking-arms of the loom in a position to engage with the hook-shaped arms on the picker-sticks when the lay is in its inward position, as described.

4. The combination with the lay of a loom, 95 shuttle-boxes at either end of the lay, swells on the shuttle-boxes, picker-sticks, means for supporting the picker-sticks, the picker-shafts, and picker-arms on the picker-shafts, of the feeler-shafts b^7 b^8 supported in bearings on the end frames of the loom, the coiled springs b^7 b^8 on the feeler-shafts, the feeler-arms b^3 b^9 on the ends of the respective feeler-shafts, the levers b^4 b^6 on the respective ends of the feeler-shafts, the arms d d' having the 100 hooked ends d' d' , the rods b^8 b^8 connecting the levers b^4 b^6 with the respective arms d d' , connections between the arms d d' and the picker-stick, and the fingers c c' having the hooked ends c' c' and supported on the picker-arms, substantially as shown and described.

In testimony whereof I have signed my name to this specification in the presence of two subscribing witnesses.

AUGUSTE DONT.
